UNITED STATES PATENT OFFICE.

JAMES DONOVAN, OF THREE RIVERS, MICHIGAN, ASSIGNOR TO THE
ROBERTS, THROP & COMPANY, OF SAME PLACE.

DESIGN FOR A FOOT-GUARD FOR SWITCHES.

SPECIFICATION forming part of Design No. 28,494, dated April 19, 1898.

Application filed March 7, 1898. Serial No. 673,015. Term of patent 14 years.

all whom it may concern:

Be it known that I, JAMES DONOVAN, a citizen of the United States, residing at Three Rivers, in the county of St. Joseph and State of Michigan, have invented and produced a new and original Design for a Foot-Guard for switches, of which the following is a specification, reference being had therein to the accompanying drawings, in which—

Figure 1 is a perspective view of a foot-guard for railway-switches, showing my design. Fig. 2 is a side elevation thereof, and Fig. 3 is a top plan view.

The leading feature of my design consists in the configuration of the same. A and B are two parallel plates of tapering

form, the plate B being smaller than the plate A and located substantially centrally thereon if viewed from the top. The two plates are connected by a web C. The plate B has an inclined end plate D. The plate A is provided with the indentations E on the sides.

What I claim as my invention is—

The design for a foot-guard for switches, substantially as herein shown and described. 25

In testimony whereof I affix my signature in presence of two witnesses.

JAMES DONOVAN.
